UNITED STATES PATENT OFFICE

HENRY SCHLACHTER, OF BEATRICE, NEBRASKA, ASSIGNOR TO DEMPSTER MILL MANUFACTURING COMPANY, A CORPORATION OF NEBRASKA

IMPELLER FOR CENTRIFUGAL PUMPS

Application filed July 5, 1929. Serial No. 375,999.

My invention relates to pumps of the centrifugal type and its object is the provision of a centrifugal pump which will be more efficient in operation than the prior pumps.

Another object of the invention is the provision of a centrifugal pump in which the balance is as nearly absolute as it is possible to obtain.

Another object of the invention is the elimination of parts and of machine work to thereby reduce the cost of manufacture without sacrificing efficiency.

Another object which I have in view is the provision whereby the total pressures on the two sides of the impeller may be either balanced or unbalanced in such a way as to create any requisite amount of end thrust.

It is also my object to provide a pump in which higher pressure may be maintained on the inner side of the gland.

Having in view these objects and others which will be pointed out in the following description, I will now refer to the drawing, in which

Figure 1 is a plan view of the face or blade side of the impeller.

Figure 2 is a sectional view of the impeller and casing, the section being taken along the diameter of the impeller.

Figure 3 is a diagram on which certain calculations are based, the calculations being intended to locate an aperture in the impeller in a position where it will have its maximum efficiency in balancing the pressure on opposite sides of the impeller or rotor.

The impeller 10 is of a more or less common form having a shroud on a central shaft 11 and spiral blades 12. The shaft 11 has its bearings in an extension 13 of the casing 14. The impeller 10 is accurately machined at its periphery for rotation in the casing wall at 15. The water drawn into the casing is engaged by the blades 12 of the impeller 10 to build up a pressure or head as is usual in pumps of this type.

While the joint at 15 between the shroud and the casing is as tight as can be made, a certain amount of leakage occurs which carries a portion of water to the rear side of the impeller. The head is produced not only on

the blade side of the impeller shroud but also on the rear side but there is normally a great difference in pressure on the two sides of the impeller shroud. It has been recognized, however, that an equality of pressure on the two sides of the impeller shroud would be desirable, but so far as I know, none of the prior constructions show effective means for equalizing these pressures, except by the use of additional parts.

Effective operation of the impeller requires that the total pressures on the two sides of the impeller shroud be balanced. The impeller shroud must not only be provided with an aperture for balancing the two pressures at that particular point, but the aperture must be so positioned and it must be of such size that the total pressures on opposite sides of the impeller shroud will be balanced.

The location of the aperture can best be determined by calculation, reference being had to Figure 3 of the drawing. Pressure or head at any point on the impeller shroud is proportional to the square of the velocity, and since the velocity is proportional to the radius, the relation may be expressed in the form of a formula, thus:

$$(1) h = kr^2,$$

in which h represents the head built up on either side of the impeller at a point at a distance r from the axis of rotation. To this, however, must be added the pressure p at the center, so that the general formula will read

$$(2) h = kr^2 + p.$$

If the radius of the impeller and the head at the periphery of the impeller be expressed by the characters a and H respectively, the formula will read

$$(3) H = ka^2 + p,$$

and the value of k may be expressed thus:

$$(4) k = \frac{H - p}{a^2}$$

Substituting the value of k in Formula (2),

$$(5) h = \frac{(H - p)r^2}{a^2} + p$$

The two curves of Figure 3, representing pressure or head on the two sides of the impeller, may be expressed thus:

$$5 \quad (6) \quad h_1 = \frac{(H_1 - p_1)r^2}{a^2} + p_1 \text{ and}$$

$$10 \quad (7) \quad h_2 = \frac{(H_2 - p_2)r^2}{a^2} + p_2$$

15 Total pressures built up by the impeller will then be represented by solids generated by the revolution of the diagram in Figure 3 about its vertical axis. The two curves of Figure 3 are parabolas, as may readily be determined by inspection of Equations (6) and (7). The revolution of the entire diagram in Figure 3 will generate a right circular cylinder while the revolution of the upper portions above the parabolas, will generate paraboloids of revolution. In the Figure 3 diagram, it will be observed that the total pressures built up on the two sides of the impeller are represented by the volumes underneath the solids described by rotating the parabolas about their vertical axis. These volumes may readily be determined by subtracting the volumes of the paraboloids from the volume of the cylinder, the equation being expressed in general terms thus:

$$20 \quad (8) \quad v = \pi r^2 H - \frac{\pi r^2 (H - p)}{2}$$

25 which may readily be reduced to the form

$$30 \quad (9) \quad v = \frac{\pi r^2 (H + p)}{2}$$

35 The total pressures, as represented by the volumes underneath the parabolas, on the two sides of the impeller must be equal. It follows that if v_1 and v_2 are equal, then

$$40 \quad (10) \quad \frac{1}{2} \pi r^2 (H_1 + p_1) = \frac{1}{2} \pi r^2 (H_2 + p_2),$$

45 or

$$46 \quad (11) \quad H_1 + p_1 = H_2 + p_2,$$

50 this being the condition necessary for equality of total pressures on the two sides of the rotor.

55 At the balance hole, the pressures or heads must be equal. In other words, h_1 and h_2 are equal. Combining Equations (6) and (7), we have

$$56 \quad (12) \quad \frac{(H_1 - p_1)r^2}{a^2} + p_1 = \frac{(H_2 - p_2)r^2}{a^2} + p_2,$$

or

$$60 \quad (13) \quad \frac{r^2}{a^2} = \frac{p_2 - p_1}{H_1 - H_2 - p_1 + p_2}$$

Under the condition imposed by Equation (11), Equation (13) becomes

$$65 \quad (14) \quad \frac{r^2}{a^2} = \frac{1}{2}$$

from whence it follows that

$$70 \quad r = \frac{a}{\sqrt{2}} \text{ or } \frac{a\sqrt{2}}{2}.$$

75 In other words, the balance hole in the impeller must be positioned a distance from the axis equal to the fraction of the radius of the impeller expressed in Equation (14).

80 The position of the aperture 16 is determined by means of the above formula. It is necessary also that the area of the aperture 16 be great enough to equalize the pressures without being any greater than is necessary. It must be large enough to permit a flow of liquid at low velocity, equal to the leakage at the peripheral joint 15, where leakage occurs at a relatively high velocity. The area of the aperture 16 is therefore determined by the area of the clearance between the periphery of the impeller shroud 10 and the casing 85 at the joint 15, or in other words, the clearance of the running joint formed by the casing and the impeller shroud. While my drawing shows only one aperture 16, it is apparent that the impeller shroud may be provided with any desired number of apertures similar to the aperture 16. These apertures must, however, be located equidistantly from the center in accordance with the above 90 formula.

95 I have also shown a very specific form of impeller together with a very specific form of casing. The principles herein set forth are, however, adapted for application to nearly all pumps of a similar kind and I wish it to be understood that Figures 1 and 2 are merely illustrative of the general type of pump. It is also obvious that it may be desirable in some cases to create unequal pressures in a certain ratio to each other on opposite sides of the impeller. If a certain amount of end thrust is desirable in one direction or the other, the balance hole 16 may be positioned in accordance with the calculations to produce the desired inequality of pressures. By creating a requisite amount of end thrust in a vertical centrifugal pump it would be possible to carry hydraulically the entire weight of the shafting and other rotating parts, thereby eliminating the load on the thrust bearings.

100 In prior impellers of this type, the pressure built up on the rear side is about one-fourth as much as that built up on the blade side, due to the fact that the water in this cavity revolves only about one-half as rapidly as it does in the blades, the pressure being proportional to the square of the velocity. This results in end thrust and in loss of 105 power, both of which objections are eliminated in the construction which I have described, and especially in the provision of a balance hole which is so positioned and which is of such size that it will effectively balance 110

the pressures on the two sides of the impeller, or which may be so positioned that the total pressures on the two sides of the impeller will be in any desired predetermined ratio to each other.

5 Having thus described my invention in such full, clear, and exact terms that its construction and operation will be readily understood by others skilled in the art to which it pertains, what I claim as new and desire to secure by Letters Patent of the United States is:

1. In a rotary pump or the like, a shrouded impeller having an opening through the shroud, the opening having an area greater than the area of the peripheral clearance of the running joint formed by the casing and the impeller shroud and being so positioned that the total pressures on the two sides of 20 said impeller shroud will be in a predetermined ratio to each other.

2. In a rotary pump or the like, a shrouded impeller having means for conducting fluid through the shroud at a velocity less than 25 that of the fluid flowing through the peripheral clearance of the running joint formed by the casing and the impeller shroud and being so positioned that the total pressures on the two sides of said impeller shroud will be in a 30 predetermined ratio to each other.

3. In a rotary pump or the like, a shrouded impeller having an opening through the shroud, the opening being located at a radial distance from the axis of said impeller equal 35 to the fraction of the radius of the impeller expressed in the equation.

$$r = \frac{a\sqrt{2}}{2}$$

40 in which r represents the radial distance of the aperture in said impeller shroud and a represents the radius of said impeller.

4. In a rotary pump or the like, a shrouded impeller having an opening through the shroud, the opening being so located as to 45 equalize the pressures on both sides of said impeller shroud, the position of the opening in the impeller being determined by the formula

50

$$r = \frac{a\sqrt{2}}{2}$$

in which r represents the radial distance of 55 the aperture in said impeller shroud and a represents the radius of said impeller.

5. In a rotary pump or the like, a shrouded impeller having an opening through the shroud, the opening being located at a radial 60 distance from the axis of said impeller equal to the fraction of the radius of the impeller expressed in the equation

65

$$r = \frac{a\sqrt{2}}{2}$$

in which r represents the radial distance of the aperture in said impeller shroud and a represents the radius of said impeller, the opening in said impeller having an area greater than the area of the clearance of the 70 running joint formed by the casing and the impeller shroud.

In testimony whereof I affix my signature.

HENRY SCHLACHTER.
